BOOK COMPANY, LIMITED, OF TORONTO, CANADA, A CORPORATION OF ONTARIO,
CANADA.

MANIFOLDING SALES-BOOK

1,157,290.

Specification of Letters Patent.

Patented Oct. 19, 1915.

Application filed July 23, 1913. Serial No. 780,639.

To all whom it may concern:

Be it known that I, EDWARD K. BOTTLE, a citizen of the United States, residing at Elmira, in the county of Chemung and State 5 of New York, have invented certain new and useful Improvements in Manifolding Sales-Books, of which the following is a full, clear, and exact description, such as will enable others skilled in the art to which 10 it appertains to make and use the same.

This invention relates to manifolding sales books and the like.

One of the objects of the present invention is to provide an efficient and simple type of 15 sales book which may be operated rapidly without soiling the fingers or duplicate copy from the carbon sheet.

A further object is to provide a practical and inexpensive sales book having a carbon 20 sheet so constructed as to prevent tearing of the sheet.

A further object is to provide a sales book of the above general character in which features of prior constructions conducive to 25 rapid and convenient manipulation are so utilized with additional elements or features that many of them are greatly improved.

Other objects will be in part obvious and 30 in part pointed out hereinafter.

The invention accordingly consists in the 35 features of construction, combinations of elements and arrangement of parts which will be exemplified in the construction herein-after set forth, and the scope of the application of which will be indicated in the following claims.

In the accompanying drawing, wherein is 40 shown two of several possible embodiments of my invention, Figure 1 is a perspective view showing the complete device in operative position with the corner of one leaf turned back in order that certain features of the invention may be more clearly seen; Fig. 2 is a plan view of one corner of the 45 carbon sheet before being bound in the book; and Fig. 3 is a similar view of a modification. Fig. 4 is a diagrammatic sectional view of the turned under corner of the carbon sheet to represent the coated and clean 50 surfaces thereof.

Similar reference characters refer to similar parts throughout the various views of the drawing.

Referring now to the drawing in detail,

and more particularly to Fig. 1, there is denoted at 1 a rear cover or support to which the leaves constituting a pad or sales book are attached, a top cover 2 is flexibly connected therewith by means of a hinge 3 whereby the device may be folded. The pad 55 comprises a plurality of sets of original and duplicate leaves of the paragon type, that is, each set comprises an original leaf 4 and a duplicate leaf 5 connected together at one end along a perforated fold 6 whereby they 60 may be subsequently separated and disposed of as desired. The opposite end of the duplicate leaf 5 projects beyond the adjacent end of the original leaf 4, permitting it to be bound by means of staples 7 into pad 65 70 form. A weakening line or row of perforations 8 permits the leaf to be detached from the stub portion bound by the staples.

Bound with and above the sets of leaves is a single faced carbon sheet 10 which is 75 adapted to be interposed between the original and duplicate leaves 4 and 5, respectively, as the sets are successively used. This carbon sheet is folded under to form a thumb 80 notch at the upper right hand corner along the dotted lines 11, Fig. 2, after first having the corner trimmed along the line 12 as shown. This turned under portion has several 85 material objects and advantages, one object being to permit the operator to grasp the upper right hand corner 13 of the next original leaf 4 more readily after the top set of leaves has received its inscriptions and has been removed from the pad along the dotted line 8. By grasping the corner 13 of the next 90 original leaf 4 with the thumb and finger of the right hand it may be pulled out or toward the operator and then laid over the carbon sheet 10 whereby the salesbook is ready to receive further inscriptions. In 95 doing this there is a tendency for the index finger to slip over the corner and under the carbon sheet and to curl or fray the edge of the notch in the carbon sheet and also the finger might become soiled by engagement 100 with the under coated surface thereof. This is particularly objectionable to clerks in dry goods stores who handle light and delicate fabrics. In reaching for the thumb notch a careless operator will sometimes scrape his 105 thumb along the carbon sheet adjacent the notch which will reproduce a smudge on the duplicate leaf therebeneath. This objection

is overcome by the present invention as the manifolding medium at that point is not in contact with the paper as will be obvious from Fig. 4. It will thus be seen that this turned under portion not only reinforces the carbon sheet where it receives the most wear, but also prevents the soiling of the fingers and duplicate leaf due to the covering of the under coated surface of the carbon sheet. It will also be noted that by trimming the carbon sheet along the line 12 before the corner is turned under the actual manifolding area will not be materially decreased.

15 In the modification shown in Fig. 3, the carbon sheet is first cut inwardly diagonally from the side along the line 15 and then folded back on the vertical dotted line 16 to occupy the position shown in dotted lines 20 17. This modification accomplishes substantially the same results in the way of reinforcing the carbon sheet at the point of manipulation and also protects the finger of the operator. Similar results may be obtained 25 in both modifications by removing or failing to apply the carbonizing medium at that corner of the sheet when making the book.

It is believed that the operation and manner of use of sales books of this character 30 will be clear to those familiar with the art from the above description. A brief statement thereof is, however, as follows: Assuming the book to be in the position shown in Fig. 1, the inscription is recorded upon 35 the upper surface of the original sheet 4 and reproduced through the carbon sheet 10 on the upper surface of the coating duplicate leaf 5. The sheet 4 is then turned down, and both the original and duplicate leaves 40 are severed along the line 8 and disposed of as desired. The operator then grasps the upper corner 13 of the next original leaf 4 and pulls the same downward from under the carbon sheet 10 and then moves it backward 45 thereover until the book is again in normal operative position as shown. The fingers of the operator are fully protected by the turned under edge, and any tendency to tear the carbon along a line parallel and 50 adjacent to the dotted line 8, or to roughen or curl the edges along the diagonal line, will be eliminated.

It is thus seen that this invention provides a simple and practical sales book adapted to 55 accomplish, among others, all of the objects and advantages set forth.

As many changes could be made in the above construction and many apparently 60 widely different embodiments of this invention could be made without departing from the scope thereof, it is intended that all matter contained in the above description or shown in the accompanying drawings shall be interpreted as illustrative and not in a 65 limiting sense.

Having described my invention, what I claim as new and desire to secure by Letters Patent is:

1. In a manifolding sales book, in combination, a pad, and a single face carbon sheet 70 having a portion of one edge turned under to form an irregularity for use as a thumb notch.

2. In a manifolding sales book, in combination, a pad, and a single faced carbon 75 sheet having a turned under corner providing a space to permit the operator to grasp the next set of leaves.

3. In a manifolding sales book, in combination, a carbon sheet, and a pad composed 80 of original and duplicate leaves, the duplicate leaves being connected or bound together at one end and the carbon sheet bound with the connected ends of the duplicate leaves, the carbon sheet having a reinforced portion at one corner adjacent its bound edge.

4. In a manifolding sales book, in combination, a carbon sheet, and a pad composed 90 of original and duplicate leaves, the duplicate leaves being connected or bound together at one end, and the carbon sheet bound with the connected ends of the duplicate leaves, the carbon sheet having a portion thereof cut and turned under to provide 95 a reinforcement therefor.

5. In a manifolding sales book, in combination, a carbon sheet, and a pad composed 100 of original and duplicate leaves, the duplicate leaves being connected or bound together at one end and the carbon sheet bound with the connected ends of the duplicate leaves, and having its upper corner adjacent its bound edge cut and turned under, 105 providing means to prevent soiling the fingers when manipulating the book.

6. In a manifolding sales book, in combination, a pad comprising a plurality of sets 110 of original and duplicate leaves bound together at one edge, the original leaf being connected to the duplicate leaf at another edge and folded back thereover, its opposite free edge terminating short of the bound edge, and a carbon sheet bound with said sets of leaves and having one of its edges 115 cut and turned under to form a reinforcement adjacent the point of manipulation.

7. In a manifolding sales book, in combination, a pad comprising a plurality of sets 120 of original and duplicate leaves bound together at one edge, the original leaf being connected to the duplicate leaf at another edge and folded back thereover, its opposite free edge terminating short of the bound edge of said duplicate leaf, and a carbon sheet cut diagonally in from one edge and turned under to cover the coated surface of the paper and protect the fingers of the operator.

8. In a manifolding sales book, in combi- 130

nation, a pad comprising a plurality of sets of original and duplicate leaves bound together at one edge, the original leaf being connected to the duplicate leaf at another edge and folded back thereover, its opposite free edge terminating short of the bound edge of said duplicate leaf, and a carbon sheet bound with said sets of leaves and having a notch along one edge and means interposed between the carbonized surface and the duplicate leaf adjacent the notch to prevent smudging the duplicate leaf when manipulating the book.

9. In a manifolding sales book, in combination, a pad comprising a plurality of sets of original and duplicate leaves bound together at one edge, the original leaf being connected to the duplicate leaf at another edge and folded back thereover, its opposite free edge terminating short of the bound edge of said duplicate leaf, and a carbon sheet bound with said sets of leaves and having a notch along one edge, and a turned

under portion of the carbon sheet interposed between the carbonized surface and the duplicate leaf adjacent the notch to prevent smudging the duplicate leaf when manipulating the book.

10. In a manifolding sales book, in combination, a pad comprising a plurality of sets of original and duplicate leaves bound together at one edge, the original leaf being connected to the duplicate leaf at another edge and folded back thereover, its opposite free edge terminating short of the bound edge of said duplicate leaf, and a carbon sheet bound with said sets of leaves and having a reinforced thumb notch on one edge.

In testimony whereof I affix my signature, 40
in the presence of two witnesses.

EDWARD KIRBY BOTTLE.
